UNITED STATES PATENT OFFICE.

MICHAEL KEARNEY, OF SPRINGFIELD, AND MELVILLE C. HAWLEY, OF ST. LOUIS, ASSIGNORS OF ONE-THIRD TO MARY S. ROGERS, OF ST. LOUIS, MISSOURI.

BOILER-FURNACE.

SPECIFICATION forming part of Letters Patent No. 393,336, dated November 20, 1888.

Application filed June 25, 1888. Serial No. 278,154. (No model.)

To all whom it may concern:

Be it known that we, MICHAEL KEARNEY, of Springfield, Missouri, and MELVILLE C. HAWLEY, of St. Louis, same State, have jointly 5 made a new and useful Improvement in Steam-Boiler Furnaces, of which the following is a full, clear, and exact description.

The improvement relates more especially to those furnaces in which a downward draft is 10 employed; and it has for its object, first, a more thorough consumption of the fuel than hitherto has been attainable in similar furnaces; second, a better circulation of the water throughout that portion of the water-space which is 15 immediately about the furnace.

To the above ends, respectively, the improvement consists mainly in making the grate-bars tubular and connecting them at both ends with the water-space of the boiler and at 20 one end of the bar applying a vertically-arranged extension thereto, and thereby forming a tubular construction whose inlet and outlet are at different levels, and whose lower portion is exposed directly to the heat of the 25 furnace, all substantially as hereinafter set forth and claimed, aided by the annexed drawings, making part of this specification and exhibiting the most desirable mode of carrying out the improvement, and in which—

30 Figure 1 is a vertical longitudinal section of a locomotive boiler, in which all the features of the improvement are jointly embodied. The section is on the line 1 1 of Fig. 2, and only that portion of the boiler is shown which 35 is needed for an understanding of the improvement; Fig. 2, a transverse vertical section on the line 2 2 of Fig. 1; and Fig. 3, a detail, being a view, partly in elevation and partly in section, showing an expansion-joint of one of 40 the grate-bars.

The same letters of reference denote the same parts.

A represents the boiler, which, saving as it may be modified by the application thereto of 45 the improvement, is of the usual construction.

B represents the fire-place; C, the fire-place door; D, the ash-pit; E, the door to the ash-pit, and F a combustion-chamber between the fire-place and the boiler-flues G, Fig. 1. The

course taken by the heat-currents and the products of combustion from the fire-place is indicated by the feathered arrows *x*, Fig. 1.

H H' represent, respectively, the upper and the lower tier of grate-bars. They are arranged horizontally or substantially horizontally at the bottom of the fire-place. In a downward-draft furnace the ashes which form at the grate are an undesirable obstruction, which, by means of the present system of grate-bars, is materially diminished. Owing 55 to the two tiers of bars arranged to bring the lower bars beneath the spaces between the upper bars the fuel is supported partly upon the bars of the upper tier and partly upon the bars of the lower tier. This causes the grate-surface to be multiplied. It also, while practically furnishing a continuous support for the fuel, provides openings between the lower bars and the upper bars, through which the ashes can drop. The fire is thus being constantly 60 and automatically cleared of its ashes while its unconsumed fuel rests upon a support beneath. The best results are obtained when the bars in each tier are spaced two inches apart or thereabout, measuring from the shell of the 65 bar, and the level of the tops of the lower bars is about one-half of an inch below the level of the bottoms of the upper bars. We have ascertained that this circulation is promoted by 70 extending the tubes at one end of the grate-bars upward in the water-space *a* of the boiler, substantially as shown at H², Fig. 1. This promotes the movement of the water over the crown-sheet *a'* downward through the space *a'* 75 at the front of the fire-place into and through the grate-bars, upward through the extensions H², and thence over the fire-place again. This circulation is especially valuable in connection with any downward-draft furnace, and notably 80 one whose bars are arranged in the zigzag style 85 shown, as in such an arrangement of the grate-bars they are particularly exposed to the heat, and a more rapid circulation of the water through the bars is at once desirable as a protection to the bars and as promotive of evaporation, as indicated by the unfeathered arrows 90 *y*. We have evaporated in use ten and one-third pounds of water to one pound of soft coal

in a boiler embodying the present improvement. The grate-bars H H', in the place of being held firmly at the ends in the shell of the boiler, are held at one or both ends in thimbles 5 I, Figs. 1 and 3, which in turn are screwed into or otherwise secured in the boiler-shell, as shown. This permits the grate-bar to elongate and to shorten at will. The joint around the end of the grate-bar is made suitably water-tight.

The openings in the ash-pit for the introduction of the steam jet to clear the ash-pit by urging the ashes toward the ash-pit door, are shown at J, Figs. 1 and 2. When not used for 15 admitting the steam referred to, they can be utilized to admit air to the combustion-chamber F, for the purpose of promoting the combustion of the gases which may form therein or come from the fire-place.

20 We claim—

1. A boiler having a furnace whose grate is composed of tubular bars arranged horizontally and at one end thereof connecting with the water-space of the boiler at the level of the 25 bars and at the other end being extended into the water-space of the boiler and therein extended upward in a tubular form to connect with the water-space of the boiler at a higher level, and by enabling the water-circulation 30 upward through said bar-extensions to be in-

dependent of that circulation which takes place in the water-space surrounding said bar-extensions to promote the water-circulation through said grate, substantially as described.

2. A boiler having a downward-draft furnace whose grate is composed of two tiers of tubular bars, the bars in the two tiers being relatively arranged as described, and the bars at one end thereof being connected with the water-space of the boiler at the level of the 35 bars and at the other end being extended into the water-space of the boiler and therein extended upward in a tubular form to connect with the water-space of the boiler at a higher level and to enable the water-circulation 40 upward through the said bar-extensions to be independent of the circulation in the water-space surrounding said bar-extensions, substantially as described.
